[57] **CLAIM**

The ornamental design for a waste receptacle with foot pedal, as shown and described.

DESCRIPTION

FIG. 1 is a right side elevational view of a waste receptacle with foot pedal showing my new design, the foot pedal being in the up position;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a top perspective view thereof;

FIG. 8 is a right side elevational view thereof with the foot pedal being in the down position;

FIG. 9 is a front elevational view of FIG. 8;

FIG. 10 is a rear elevational view of FIG. 8;

FIG. 11 is a left side elevational view of FIG. 8;

FIG. 12 is a top plan view of FIG. 8;

FIG. 13 is a bottom plan view of FIG. 8; and,

FIG. 14 is a top perspective view of FIG. 8.

FIG. 2FIG. 7FIG. 1FIG. 3FIG. 4FIG. 5FIG. 6

FIG. 9FIG. 14FIG. 8FIG. 10FIG. 11FIG. 12FIG. 13
